UNITED STATES PATENT OFFICE.

OSCAR P. NYSTROM, OF HOLLAND, MICHIGAN, ASSIGNOR TO HOLLAND FURNACE COMPANY, OF HOLLAND, MICHIGAN, A CORPORATION OF MICHIGAN.

FURNACE-GRADE CONSTRUCTION.

1,332,353.

Specification of Letters Patent.

Patented Mar. 2, 1920.

Application filed May 10, 1918. Serial No. 233,661.

To all whom it may concern:

Be it known that I, OSCAR P. NYSTROM, a citizen of the United States of America, residing at Holland, in the county of Ottawa and State of Michigan, have invented certain new and useful Improvements in Furnace-Grate Constructions; and I do hereby declare the following to be a full, clear, and exact description of the invention, 5 such as will enable others skilled in the art to which it appertains to make and use the same.

This invention relates to a novel grate construction for furnaces. A primary object and purpose of this invention is to provide, in a grate for furnaces, means for mounting the grate between the furnace fire-pot and the ash-pit, together with a means for actuating the grate such that a combined 10 rotary and oscillating movement of the grate is obtained, the same being particularly effective to shake down the ashes and clinkers into the ash pit. Another object of the invention is to provide a novel means 15 for mounting the grate such that it may be very easily applied and removed, while at the same time the construction permits a tilting of the grate so that the entire contents of the fire-pot may be dumped at any 20 time into the ash pit, the grate being so mounted as to be practically balanced and requiring little or no effort in carrying out this dumping movement. A further object of the invention is to provide a means for 25 holding the grate in its normal operative position which is of simple and novel character, and one which is very easily accessible for disconnection at any time that it is desired to dump the contents of the fire-pot 30 into the ash pit. Many other objects and purposes together with novel constructions for attaining the same, and directed particularly to an extremely simple, effective, and economical grate construction, will appear 35 as the description of the invention progresses, reference being had to the accompanying drawings showing a preferred construction embodying the invention, in which—

40 Figure 1 is a perspective view, with parts broken away and shown in section, of the furnace ash pit, and base construction forming a part of the structure of my invention.

45 Fig. 2 is a longitudinal vertical section taken therethrough.

Fig. 3 is a side elevation, partly in section, of the grate, supporting bar therefor and operating mechanism for actuating the same.

Fig. 4 is a front elevation of the assembled grate structure and ash pit.

Figs. 5 and 6 are, respectively, enlarged front and plan views of the grate supporting bar, and

Fig. 7 is an enlarged view of the oscillating hook with which the grate operating rod is detachably associated.

Like reference characters refer to like parts in the several views of the drawings.

In the construction an ash pit, preferably, 70 of cast iron is provided having cylindrical vertical walls 1 from which, at the front side projects an extension comprising vertical walls 2 connected at their upper edges by a top wall 3, the ash pit back of the top 75 having an open upper side in which the grate is mounted below the furnace fire-pot as will be understood by all familiar with furnace construction. At diametrically opposed points near the upper edges of the 80 vertical walls 1 of the ash pit, inwardly extending sockets 4 are cast, having open upper sides adapted to receive the ends of a grate supporting bar as will hereafter appear. From the top 3 an eye member 5 depends, the same being cast integral with said top. A hook member 6 having upper and lower hooks 7 and 8 is suspended from the eye 5, the upper hook 7 being of smaller size than the lower hook and passing 85 through the eye of member 5, it being apparent that the member 6 has a free swinging movement and may be turned to various positions with respect to the top 3 from which it is suspended. 90

95 A grate supporting bar 9 is adapted to be received at its ends in the sockets 4 and supported a distance above the bottom of the ash pit. The ends 10 of the bar 9 are fashioned to enter the open sockets 4, shoulders 11 being provided to preclude any longitudinal movement of the bar with respect to the ash pit. At its middle point and on the upper side of the bar a tapered projection or post 12 is cast, the same extending 100 and tapering upwardly as shown.

105 The grate 13 is of circular type having various slots and openings for the passage of ashes. The grate tapers upwardly toward its center. On the under side of the 110

center of the grate a socket 14 is made, adapted to loosely receive the upper end of the post 12, while a lug 15 is cast integral with and depends from the front side of the grate, it having a horizontal opening therethrough through which a tubular rod 16 may loosely pass, the same also being adapted to enter the open upper side of the hook 8 whereby the rod is supported in substantially horizontal position. At its outer end this rod is equipped with a handle 17.

In operation the handle 17 may be grasped and the grate turned back and forth about the vertical axis of the post 12 imparting a circular motion thereto, while at the same time the hooked member 6 is turned back and forth about member 5 causing a progressive elevation of the handle to each side of its central lowermost position. It is evident that not only is a rotary back and forth motion given to the grate, but that it is progressively tilted and oscillated about the axis of the post 12 simultaneously with the rotary movement. This is a very effective action to stir and dislocate ashes and clinkers from the grate causing the same to drop through into the ash pit; and particularly as the outer edges of the grate are raised and lowered with respect to the firepot which is located above the ash pit, thus causing any clinkers which gravitate to the outer edges of the grate to be worked out between the outer edges of the grate and the fire-pot.

If at any time it is desired to dump the entire contents of the fire-pot, all that is necessary is to disconnect the rod 16 from the hook 8 letting the forward side of the grate tilt downwardly, while the rear side moves in an upward direction, the bar 9 turning about a horizontal axis as is obvious. It will be noted in this connection that the grate is balanced with respect to the bar 9 and that to either raise or lower the same requires practically no effort. Furthermore, the hook member 6 is centrally located at the front of the ash pit extension directly behind the door (not shown) which normally closes the front side thereof and can be very readily operated by hand to disconnect rod 16 from the lower hook 8. The hook member 6 may be readily connected to or removed from the eye 5 in certain positions thereof, the rod 16 is readily removable from the grate, the grate may be lifted easily off of the post 12, while the bar 9 may be connected with or removed from the sockets 4 without the use of any tools of any kind, this permitting a very quick and economical assembling of the parts or a ready replacement of the same should any of the parts become burnt out or otherwise rendered useless. All of these features of utility, together with the extreme simplicity of construction and the

minor number of parts needed, render the grate construction one of great value. And particularly the combined rotary and oscillatory movements which may simultaneously be given to the grate, make the construction one of particular efficiency for furnaces.

Various changes in detail of construction may be resorted to without departing from the invention and accordingly, I do not wish to be limited to the exact specific construction shown and described, but consider myself entitled to all modifications of structure falling within the scope of the appended claims defining the invention.

I claim:

1. In combination, a furnace ash pit having an open top, a front extension thereto having a closed top, socket members projecting inwardly from opposite sides of the ash pit, a bar provided with a central vertical upwardly tapered post loosely mounted and seated at its ends in said socket members, a circular grate having a socket on its under side positioned over the bar, the upper end of the post loosely entering said socket on the grate, said grate at its front side being provided with a downwardly extending lug having a horizontal opening therethrough, an eye-member depending from the top of the ash pit extension, a hook member formed with open hooks at both ends pivotally suspended from said eye-member, one hook passing loosely through the eye of said member, and an operating rod passing loosely through the front depending lug on the grate and detachably received and held by the lower hook of said hook member, substantially as described.

2. In combination, a furnace ash pit having an open top, a front extension thereto having a closed top, a socket member located one at each side of the ash pit, a bar pivotally mounted at its ends in said socket members, said bar having a central vertical post, a circular grate provided with a central socket on its under side located over the bar, the upper end of the post loosely entering the socket, a member detachably and pivotally connected to and depending from the top of the extension, said member having a hook at the lower end thereof, and an operating rod detachably connected at its rear end with the grate and received and held between its ends by said hook, substantially as described.

3. In combination, a furnace ash pit having an open top, a front extension thereto having a closed top, a bar pivotally mounted to turn on a horizontal axis between the sides of the ash pit, said bar having a central upwardly extending post, a grate provided with a central socket on its under side loosely mounted on the post, the upper end of the post entering the socket, a member

- pivottally connected to and depending from the top of said ash pit extension, said member at its lower end being formed with a hook, and a rod connected at its rear end 5 with the grate and detachably received and held by said hook at a point between its ends, substantially as described.
4. In combination, a furnace ash pit having an open top, a front extension thereto having a closed top, a bar positioned horizontally across, and mounted to turn on a horizontal axis between the sides of the ash pit, a grate mounted on and above the bar to turn freely and tilt partially about a vertical axis located substantially midway between the ends of the bar, a member pivottally connected to and suspended from the top of the ash pit extension, and an operating rod connected at its rear end to the front 10 part of the grate and detachably connected between its ends to the lower end of said member.
5. In combination, a furnace ash pit having an open top, a bar positioned horizontally across the ash pit and mounted to turn on a horizontal axis between the sides of the ash pit, a centrally located post on the bar extending upwardly therefrom, a grate having a centrally positioned socket on its under side located above the bar with the upper end of the post loosely entered into the socket, an operating rod attached to the grate and extending forwardly therefrom, and means pivottally mounted above the rod 15 with which the rod has detachable engagement at a point below its point of pivotal mounting whereby said rod may be swung from side to side about the pivot of said means, substantially as described.
- 40 6. In combination, a furnace ash pit having an open top, a bar positioned horizontally across, and mounted to turn about a horizontal axis between the sides of the ash pit, a grate mounted on the bar to turn about a vertical axis, and means to turn the grate back and forth about said vertical axis, and simultaneously tilt the grate slightly with respect to said vertical axis, said means being detachable and serving to hold the grate in substantially horizontal position, substantially as described.
7. In combination, a furnace ash pit having an open top, a bar located horizontally across the open end of the ash pit and mounted at its ends on the sides of the ash pit to turn about a horizontal axis, a circular grate rotatably mounted above and on the bar to turn about a vertical axis, an operating rod connected at its rear end to the front part of the grate, and means to detachably and pivottally support said rod at a point above the rod and between its ends whereby it may be oscillated back and forth from side to side, or permitted to drop to tilt the grate about the horizontal axis of the bar, substantially as described.
8. In combination, an ash pit having an open upper side, a grate located in said open upper portion of the ash pit, means for mounting the grate so that the same may turn about a vertical axis and simultaneously tilt the grate slightly with respect to said vertical axis, and means for operating the grate to turn it about said vertical axis and simultaneously tilt it with respect to the said vertical axis, the turning and tilting movements taking place at the same time and by operation of said means, substantially as described.

In testimony whereof I have affixed my signature.

OSCAR P. NYSTROM.
